(57) **CLAIM**

The ornamental design for a microscope straddle stand, as shown and described.

DESCRIPTION

FIG. 1 is a perspective view of an ornamental design for a microscope straddle stand in a collapsed position.

FIG. 2 is a perspective view of the ornamental design for the microscope straddle stand with a microscope and in a collapsed position.

FIG. 3 is a front view of the ornamental design for the microscope straddle stand in a collapsed position.

FIG. 4 is a back view of the ornamental design for the microscope straddle stand in a collapsed position.

FIG. 5 is a right side view of the ornamental design for the microscope straddle stand in a collapsed position.

FIG. 6 is a left side view of the ornamental design for the microscope straddle stand in a collapsed position.

FIG. 7 is a top-down view of the ornamental design for the microscope straddle stand in a collapsed position.

FIG. 8 is a bottom view of the ornamental design for the microscope straddle stand in a collapsed position.

FIG. 9 is a perspective view of the ornamental design for the microscope straddle stand in an extended position.

FIG. 10 is a perspective view of the ornamental design for the microscope straddle stand in an extended position.

FIG. 11 is a front view of the ornamental design for the microscope straddle stand in an extended position.

FIG. 12 is a back view of the ornamental design for the microscope straddle stand in an extended position.

FIG. 13 is a right side view of the ornamental design for the microscope straddle stand in an extended position.

FIG. 14 is a left side view of the ornamental design for the microscope straddle stand in an extended position.

FIG. 15 is a top-down view of the ornamental design for the microscope straddle stand in an extended position; and,

FIG. 16 is a bottom view of the ornamental design for the microscope straddle stand in an extended position.

The broken lines shown throughout the views represent the portions of the microscope straddle stand that form no part of the claim.
